COMBINED COOLER AND DISPENSER FOR LIQUIDS

Vance V. Elkins, Paoli, Pa., assignor to Charles E. Hires
Company, a division of Consolidated Foods Corpora-
tion, Philadelphia, Pa., a corporation of Maryland

Filed Jan. 5, 1961, Ser. No. 63,457

Term of patent 7 years

(Cl. D2—3)

FIG.1.

FIG.2.

FIG.3.

FIG.4.

FIG. 1 is a view in front elevation of a combined cooler and dispenser for liquids embodying my new design;

FIG. 2 is a view in side elevation thereof;

FIG. 3 is a front perspective view thereof; and

FIG. 4 is a fragmentary bottom rear perspective view thereof.

The upper portion of the rear of the article is identical to the front thereof. The top, not shown, comprises a substantially plain inset cover element.

My design for the combined cooler and dispenser for liquids shown is characterized by the portions thereof beneath the barrel-shaped upper body portion.

I claim:

The ornamental design for a combined cooler and dispenser for liquids, substantially as shown and described.
